UNITED STATES PATENT OFFICE.

FRANCIS H. RICHARDS, OF HARTFORD, CONNECTICUT, ASSIGNOR TO ECKLEY B. COXE, OF DRIFTON, PENNSYLVANIA.

FEED MECHANISM.

SPECIFICATION forming part of Letters Patent No. 404,365, dated May 28, 1889.

Application filed January 10, 1889. Serial No. 295,920½. (No model.)

To all whom it may concern:

Be it known that I, FRANCIS H. RICHARDS, a citizen of the United States, residing at Hartford, in the county of Hartford and State 5 of Connecticut, have invented certain new and useful Improvements in Hand-Controlled-Power Feed Mechanism, of which the following is a specification.

This invention relates to, and its object is 10 to furnish, mechanism adapted to actuate the feed-shafts of heavy machines—such as large machine-tools and the like—wherein the movement of such shafts should be controlled by the hand of the operator, while the power 15 required is beyond his ability or convenience; and it consists in certain improvements whereby the operator, by moving one part, as a hand-wheel, by hand, causes power to be automatically applied to another part to produce a corresponding motion, as hereinafter 20 more fully set forth.

In the drawings accompanying and forming a part of this specification, Figure 1 is a 25 plan view of a mechanism embodying my improvements. Fig. 2 is a front elevation of the same. Fig. 3 is a vertical longitudinal section through the clutch-actuating devices. Fig. 4 is an end elevation, as seen from the right hand in Figs. 1, 2, and 3. Figs. 5 and 30 6 are side and sectional views, respectively, of one of the stop-collars.

Similar characters designate like parts in all the figures.

The frame-work of my improved mechanism will in practice generally be some part of the frame-work of the machine in connection with which the mechanism may be employed; but the several operative details may be assembled upon a bed-plate, A, provided with 35 suitable bearings and supports therefor. The primary driving-shaft or counter-shaft 2 is or may be carried in bearings 3 and 5 and driven by a pulley, 4, fixed thereon. From this shaft two reversely-operated friction- 40 wheels 6 and 8 are driven by suitable gearing or some well-known equivalent therefor. For this purpose I make said wheels to be gear-wheels, the wheel 8 being driven by pinion 10 on shaft 2, and the wheel 6 driven 45 reversely by the pinion 12 through the intermediate gear, 11, that is carried on stud 9,

fixed in the frame-work. The said friction-wheels are carried on the opposite ends of the main driving-shaft 15, which shaft is carried in the bearings 13 and 14, and has fixed 55 thereon a worm, 7, that meshes with and drives the worm-wheel 17 on the feed-shaft B. Said wheels are fitted to turn freely on said shaft contiguous to the bearings 13 and 14, respectively, and a nut, 19, Fig. 3, is provided 60 to retain the wheel 6 in proper position longitudinally of the shaft. Sliding friction-rings 16 and 18 are splined to the shaft 15 and constructed to be slid thereon into frictional engagement with the friction-wheel. 65 A suitable construction and arrangement of this detail is shown in the drawings, and will be understood from Fig. 3, in which 21 is the “spline” or key in shaft 15, and over which the disk 16 is fitted to slide. 22 is a disk af- 70 fixed to the hub of the disk 16 by screws 23. 25 is a shipper-rod or connecting-rod connected to the ring 16 by said disk 22 and by the nut 24.

The minor details are represented to be the 75 same for each of the friction-disks 16 and 18, and hence, so far as such details are shown, the same are similarly designated. The wheels 6 and 8 being revolved continuously in opposite directions, by sliding the rod 25 80 (within the hollow shaft 15) in one direction one friction-disk is engaged with its wheel and the shaft B correspondingly rotated, and by a reverse movement of said rod 25 the opposite driving mechanism is brought into ac- 85 tion and the shaft B is reversely rotated. For thus operating the said rod 25, and through it the said shaft, I employ devices wherein the connection between the hand-wheel and that rod is made through a part whose motion is a 90 resultant of two motions, one being communicated from the hand-wheel and the other from the driven mechanism. By this means I obtain the result which constitutes the prin- 95 cipal object of my present improvements. The following is a description of the best form of devices now known to me for carrying into effect my said invention.

The shaft 15 has an enlargement, 26, and carries an internally-threaded shell, 28, journaled at 27 on said shaft at one end of the enlargement 26. A gear, 30, is affixed to the 100

said shell, and is journaled at 29 on shaft 15 at the opposite end of said enlargement. When in place and secured together, (by screws 31 or otherwise,) these two parts constitute in effect one piece of machinery, fitted to revolve freely on shaft 15 and held in place longitudinally thereof by the enlargement 26. A pinion, 32, meshing with said gear, a shaft, 33, carrying said pinion 32, the bearing 34, supporting said shaft 33, and hand-wheel 35, fixed on shaft 33, are provided to turn said shell by hand. A sliding collar, 36, Fig. 3, is fitted upon said portion 26 of shaft 15, and has a thread meshing with that inside of the shell 28. This collar stands over a slot or mortise, 37, in said part 26, and has a key, 38, which passes through it and said mortise to rigidly connect the same with the sliding clutch-rod 25. Said key 38 also serves as a means for preventing the rotation of said collar 36 on said shaft 15. These several parts together furnish or constitute a means for imparting the required longitudinal motion to the rod by the turning of said shell 28 on said shaft 15, and the collar 36 constitutes the part above referred to, whose motion is the resultant of two motions, one being communicated thereto from the hand-wheel 35 and the other from the shaft 15, for if the shaft 15 be not revolving that collar may be moved by hand, as set forth, and if said shaft be revolving and the shell 28 be held from revolving, then said collar will be moved by the shaft; but if the shaft be revolving at one speed and the shell at another speed the longitudinal motion of the said collar will be a resultant of the said two movements. These several elements are so proportioned and organized that if the hand-wheel be turned in one direction—as, for instance, to engage friction-wheel 6—said wheel 6 will turn shaft 15 in a direction to move rod 25 toward the right hand and thus disengage said driving-wheel. Consequently, if shaft 15 is to be turned for any given time, the hand-wheel must be turned correspondingly during that time, and if the hand-wheel be turned slower than the motion (relatively) of wheel 6 then the friction-surfaces of parts 6 and 16 will slip one on the other by the difference between the relative motions of the said parts 6 and 35; and thus, as it will now be seen, the motion of the shaft 15 and the parts driven thereby is controlled by hand, while the required power for actuating said parts is furnished by the driving apparatus.

For adapting my improved mechanism to more general and convenient use, I provide the same with devices or apparatus for holding the shell or revolving nut 28 normally in a certain position circumferentially on the shaft 15. These devices I make in duplicate sets and place one set at either end of said revolving nut. The said devices in one set are designated by figures, and of the other set by the same figures, with the addition thereto of a "prime" mark. Each set consists of a

stop-key, 40, formed or fixed on shaft 15, a stop or lug, 41, on the revolving nut, a stop-collar, 42, engaging with said key 40 and lug 41 and having a limited movement on said shaft 15 and relative to said key and lug, a return-spring, 44, carried on the shaft 15 and connected at 43 to revolve the collar 42, and an adjustable collar, 45, connected at 46 to the opposite end of said spring, whereby the same may be put under sufficient tension to turn the stop-collar 42 through the limited movement aforesaid, and, if need be, overcome at the same time the resistance of the said revolving nut, together with the inertia of the hand-wheel.

The collar 45 may be clamped by screws 47 to the shaft 15 in a well-known manner.

The spring 44 is or may be an ordinary spiral torsion-spring.

The proper construction of the stop-collar is shown in Figs. 5 and 6. A section of the inner surface is cut away, as at 48, to permit of the necessary turning motion of the collar 42 on the shaft 15 and against the stop-key 40. Another section at 49 is cut away for the stop 41 on the revolving nut. The normal arrangement of these parts when the mechanism is idle is shown best in Fig. 1. In this case the stop-collars 42 and 42' stand against the respective stop-keys of the shaft 15 and against the opposite sides of the said lugs or stops 41 and 41' of the said revolving nut. In this position (if the shaft 15 should be turned by any means other than the friction-wheels) the springs 44 should be under tension enough to normally hold the said nut and accessory devices in the middle position shown, and also to turn the wheel 35 when this wheel is not controlled by hand.

In operating the mechanism, the wheels 6 and 8 being revolving as described, the operator seizes the hand-wheel 35, and through this turns the nut 28 on shaft 15, thereby turning the stop-collar 42 away from its stop-key 40, and engaging one of the friction-wheels, which engagement starts revolving, as before set forth, the shaft 15. On releasing wheel 35 the spring 44 retracts the stop-collar, and through this and stop 41 turns back the nut 28 to disengage the friction-wheel and stop the mechanism. The said return movement of the said nut 28 is limited by the opposite lug thereon, for when the nut 28 is turned in one direction one stop-collar is carried therewith, but the other does not follow beyond the middle position shown in Fig. 1. The extent of the movement of the wheel 35 preceding the starting of shaft 15 is determined of course by the particular proportions and construction or adjustment of the several details, and may be varied within considerable limits at the discretion of the constructor.

Having thus described my invention, I claim—

1. In a mechanism of the class specified, the combination, with a driven shaft and re-

versely-operating driving apparatus, substantially as described, of a sliding collar connected to engage and disengage said apparatus, and a revolving nut carried in a fixed position longitudinally on said shaft, constructed to actuate said collar and adapted to be revolved by hand, all substantially as described.

2. In a mechanism of the class specified, 10 the combination of the shaft 15, driving apparatuses, substantially as described, for reversely revolving said shaft, collar 36, connected to engage and disengage said apparatuses one at a time, the revolving nut, and 15 the hand-wheel connected to revolve said nut independently of and turn the same on said shaft, all substantially as described.

3. In a mechanism of the class specified, the combination, with the shaft 15, provided 20 with a sliding collar, a clutch-rod, and driving apparatuses, substantially as described, of the revolving shell constructed to actuate said collar and adapted to be revolved independently of said shaft, and devices, substantially as described, operating to normally hold 25 said shell in a middle position, as set forth, circumferentially of said shaft, substantially as described.

4. In a mechanism of the class specified, 30 the combination of the shaft 15, having a stop-key, rod 25, collar 36, connected to said rod, the revolving nut actuating said collar and having lug 41, stop-collar 42, engaging 35 said stop-key and lug, and a spring actuating said stop-collar, substantially as described.

5. In a mechanism of the class specified, the combination of shaft 15, collar 36, connected to engage the driving-wheels, substantially as described, the revolving shell actuating said collar, and oppositely-disposed 40 stop-collars actuated, substantially as described, to normally hold said shell in a middle position circumferentially of said shaft, substantially as described.

6. In a mechanism of the class specified, 45 the combination, with a frame-work, of the main shaft 15, wheels 6 and 8, clutches 16 and 18, rod 25, collar 36, connected to said rod, and a revolving part, substantially as described, carried on said shaft and adapted to be 50 revolved independently of the shaft to actuate said collar, all substantially as described.

7. In a mechanism of the class specified, the combination, with the shaft 15, having 55 enlargement 26 and slot 37, of the rod 25, key 38, collar 36, and a revolving shell, substantially as described, actuating said collar and taking its bearings on said shaft at either end of said enlargement, substantially as described.

8. In a mechanism of the class specified, the combination, with the shaft 15, having 60 key 40, of the shell having lug 41, and stop-collar 42, having spaces 48 and 49, substantially as described.
